(57) **CLAIM**

The ornamental design for a side rail for a vehicle, as shown and described.

DESCRIPTION

FIG. 1 is a front right side perspective view of the side rail enlarged 2:1 with respect to FIGS. 3-8.

FIG. 2 is a rear left side perspective view of the side rail enlarged 2:1 with respect to FIGS. 3-8.

FIG. 3 is a rear top side perspective view of the side rail.

FIG. 4 is a front bottom side perspective view of the side rail.

FIG. 5 is a left side elevation view of the side rail.

FIG. 6 is a top plan view of the side rail.

FIG. 7 is a right side elevation view of the side rail.

FIG. 8 is a bottom plan view of the side rail.

FIG. 9 is a rear elevation view of the side rail enlarged 3.5:1 with respect to FIGS. 3-8; and,

FIG. 10 is a front elevation view of the side rail enlarged 3.5:1 with respect to FIGS. 3-8.

The broken lines represent portions of the side rail that form no part of the claim.
